UNITED STATES PATENT OFFICE.

CHARLES H. AYARS, OF SALEM, NEW JERSEY, ASSIGNOR TO AYARS MACHINE COMPANY, OF SALEM, NEW JERSEY, A CORPORATION OF NEW JERSEY.

CAN-FILLING MACHINE.

1,217,884.

Specification of Letters Patent. Patented Feb. 27, 1917.

Application filed January 30, 1914. Serial No. 815,395.

To all whom it may concern:

Be it known that I, CHARLES H. AYARS, a citizen of the United States, residing at Salem, in the county of Salem and State of New Jersey, have invented certain new and useful Improvements in Can-Filling Machines, of which the following is a specification.

This invention relates to an improved machine for filling cans with fruits or vegetables.

The present invention has particular reference to that kind of a machine which is shown in U. S. Patent 722,075 granted to me March 3rd, 1903, but is an improvement in many respects on machines of that character.

One object of the present invention is to provide an improved construction of filling machine with practically a double filling capacity over the machine of my said patent without however duplicating all of the parts.

Another object is to provide improved means for presenting the cans to the filling mechanism; to hold the cans in a somewhat inclined position during the filling thereof so as to facilitate the overflow from the cans that are being filled and insure that the cans will receive a uniform quantity of material.

A further object is to provide improved means for presenting a plurality of cans at a time to the filling mechanism and to improve the means for ejecting the cans after they have been filled.

I have also shown in connection with the present invention an improved can feed device adapted for handling either the headed end cans or for feeding cans known in the trade as "sanitary cans" which latter cans have one end or head entirely removed during the filling operation, but the present application makes no claim to this feed mechanism as that forms the subject of a companion application executed and filed simultaneously herewith.

The invention is illustrated in the accompanying drawings wherein,

Figure 1, shows the improved machine in side elevation.

Fig. 2, illustrates the same in front elevation.

Fig. 3, shows a side elevation of the lower part of the machine as viewed from the right hand side of Fig. 2.

Fig. 4, illustrates in top plan, the mechanism shown in Fig. 3.

Fig. 5, shows a vertical sectional detail through one of the tapered discharge tubes and also through the intersecting plunger tube and the overflow device.

Fig. 6, is a sectional plan view of the overflow device,—the section being taken on the line 6—6 of Fig. 5, and

Fig. 7, shows a bottom plan view of the overflow device.

Referring to the drawings by numerals, 8, designates a frame, shaped to form bearings and supports for the various parts of the machine and to hold an inclined hopper, 9, in an elevated position. The hopper has a plurality of discharge tubes, 10, which incline downwardly therefrom and is also provided with a plurality of plungers, 11,—one for each discharge tube.

A suitable cross-head, 12, connects the upper ends of the plungers and a connecting rod, 13, is slidably sustained in brackets, 14, at the under side of the hopper so that its reciprocating movement may be imparted to the plungers through an operating rod, 15. The operating rod, 15, is bent laterally and extends downwardly and forwardly, as seen in Figs. 2 and 3 of the drawings and its lower end pivotally engages an adjustable block, 16, which latter is carried by a cam-frame, 17. This cam frame is pivotally sustained at its lower end by a rock shaft, 18, which latter derives its rocking motion from the frame as will presently be explained.

A horizontal cam shaft, 19, has its opposite ends sustained in the vertical side members of the frame, 8, and said shaft extends through the cam frame, 17, as clearly shown in Fig. 3, of the drawing so that a cam, 20, on said shaft may turn in a vertical plane in said cam frame and thereby oscillate said frame in a vertical plane and thus impart a longitudinal reciprocating movement to the operating rod, 15, to reciprocate the plungers, 11.

The lower end of each discharge tube, 10, is intersected by a plunger tube, 21, each of which latter has a plunger, 22, therein which cross the lower end of said discharge tubes as shown in section in Fig. 5. Each plunger, 22, is provided with a rod, 23, which projects upwardly from its upper end and a cross-

head, 24, connects the ends of said rods, as clearly shown in Fig. 2, of the drawing.

Suitable bracket bearings, 25, and, 26, respectively are carried by upper and lower portions of the frame so that a rod, 27, may extend through said bearings and have a reciprocating movement therein. The upper end of this rod, 27, is rigidly engaged with the cross-head, 24, while near the lower end, 10 said rod carries a block or head, 28, which has side recesses therein so that prongs, 29, which are formed on the end of a rock lever, 30, may engage the block or head and cause a longitudinal reciprocation of the plunger rod, 27, each time the rock lever, 30, is actuated.

The rock lever is carried by a rock shaft, 31, which is supported in suitable bearings, 32, and an arm, 33, projects rearwardly from 20 said rock shaft and carries a roller, 34, which has position in a side groove of a cam, 35, which latter is carried on the horizontal cam-shaft, 19. It will therefore be understood that the cam, 35, will rock arm, 33, 25 shaft, 31, and rock lever, 30, to cause a longitudinal reciprocation of the rod, 27, and a like movement of the plungers, 22.

The lower end of each plunger tube, 21, carries an overflow shell, 37, which latter 30 has a bottom flange or plate, 38, that extends both forwardly and rearwardly with respect to the plunger tube, and through which the plunger, 22, projects slightly when the latter is in its lowermost position as 35 shown in Fig. 5. On the under side of the bottom plate, 38, there is a gasket, 39, which latter encircles the opening through which the plunger, 22, extends so that a can being 40 filled may be seated against the gasket to form a sufficiently tight joint to prevent leakage.

The overflow shell and its bottom plate have an inclined position with the front-end higher than the rear end and at the rear or 45 lower side of the plunger, 22, said bottom plate has an overflow passage, 40, which opens upwardly into a rearwardly-extending chamber, 41, of the shell, as clearly shown in Figs. 5 and 6 of the drawings. The rear 50 end of the shell-chamber, 41, has a bottom outlet, 42, and a nozzle, 43, projects below the inclined bottom so as to allow the escape of materials from the chamber.

By referring to Figs. 1, 6 and 7 of the 55 drawings, it will be noted that the bottom plate, 38, of the overflow shell is provided with centering lugs, 44, and, 45, respectively by means of which the cans to be filled may be centered and properly positioned about 60 the under side thereof for filling.

The machine is provided with a flat stationary table, 46, shown best in Figs. 3 and 4 of the drawing, and a movable table, 47, is pivotally sustained at its rear edge on a horizontal bar, 48, so as to swing into a plane

flush with the stationary table or be moved into an inclined plane with respect to said stationary table.

The movable table, 47, is provided with an opening, 49, which extends in a direction 70 from front to rear and a wall, 50, extends upwardly from the table and around said opening whereby to form a guide at each side of the opening.

The purpose of this walled opening is to 75 permit the plunger-actuating rod, 27, to pass therethrough without however interfering with an up and down swinging motion that is to be given the table as will presently be described. At the rear end the wall, 50, has 80 a V-shape, 51, so as to divide the cans as they are fed onto the movable table and prevent crushing the same during such movement against the wall at the inner end of the table-opening.

85

Beneath the stationary table, and extending horizontally thereunder is a rock-shaft, 52, which carries an arm, 53, that projects forwardly and curves upwardly under the movable table, 47. The forward or free end 90 of this arm, 53, is provided with a roller, 54, on which the bottom of the movable table, 47, rests so that by rocking the shaft, 52, in a direction to throw the free end of arm, 53, upwardly, will cause the table, 47, to be 95 swung upwardly as shown in Figs. 1 and 3 of the drawings.

The horizontal shaft, 19, carries a cam, 55, while the rock-shaft, 52, is provided with an arm, 56, which extends downwardly in front 100 of said cam and carries a roller, 57, which contacts with the face of the said cam, at least during the period that said table, 47, is held raised.

Another arm, 58, is loosely carried on the 105 rock-shaft, 52, and extends downwardly at the rear of the cam, 55, and a spring, 59, connects the lower ends of said arms, 56, and, 58, so as to yieldingly draw said free ends of the arms toward each other. A stop lug, 60, 110 is provided on arm, 58, so as to project at the rear of arm, 56, as seen in Figs. 1 and 2 of the drawings, and the purpose of this stop is to form a yielding abutment against which the arm, 56, may strike when it 115 is moving rearwardly and lowering the table, 47.

A feed cam, 61, is also carried on cam-shaft, 19, and has a side groove in which a roller, 62, of a rock lever, 63, rides. This rock-lever, 63, has its lower end pivotally mounted on shaft, 18, while its upper end projects through a horizontal slot, 64, in the table, 46, and pivotally engages the under side of a feed plunger, 65. The feed plunger 120 is sustained in horizontal guides 66, on top of the table, 46, and the forward end of this plunger has two heads, 67, each of which engages a can that has been placed in front 125 of it so that on making a forward stroke 130

both cans will be moved forward toward the movable table.

From the foregoing explanation each revolution of the feed-cam, 61, will cause the feed plunger to make one forward stroke to feed two empty cans forward and a return stroke to permit the placing of two more cans in front of it to be fed forward.

A spring, 68, is provided at the upper end of the rock lever, 63, to aid in returning the same and the feed plunger, 65, to their rearward position.

A bracket, 69, extends vertically from the table, 46, and sustains a horizontal friction plate, 70, which has an upturned yielding end, 71. This plate, 70, has position in front of the plunger-heads, 67, when the latter are at their rearmost position as shown in Figs. 3 and 4 of the drawing, and said plate is sustained in a horizontal plane so as to bear on the open tops of the empty cans as the latter are fed or moved into position in front of the plunger heads, 67. A stop plate, 72, is provided on the under side of plate, 70, to stop the cans fed thereunder.

The empty cans are fed, open ends up, by any desirable can-feed mechanism, but I have shown an improved construction of feed-mechanism which forms the subject of a separate application because it may be utilized in filling machines having constructions very different from the filling mechanism herein shown.

When however the cans are fed so as to place two empty cans in front of the plunger heads, 67, the latter are moved forward, thereby pushing the two empty cans ahead of them and onto the movable table, 47. During this forward movement, the V-shaped end, 51, of wall, 50, divides the cans, causing one can to pass onto the movable table at one side of the wall, 50, and the other can to pass onto the said table at the opposite side of said wall. When pushed onto the movable table, suitable clamp devices, 73, engage the cans and hold them against accidental displacement while the table is raised and lowered. When the next two cans are pushed onto the movable table, 47, the two previously placed thereon will be moved forward to filling position where they will be engaged by yielding clamps, 74, which hold them during the filling operation.

While held by the clamps, 74, the table, 47, is elevated so as to seat the open ends of the two foremost cans beneath the gasket, 39, on the bottom of the overflow shell. At this time the cans are held in an inclined position.

The filling mechanism is then actuated to allow the material to pass from the hopper through the discharge tubes, 10, and into the plunger tubes, from which latter such material is forced by plungers, 22, into the

inclined cans. The plungers, 22, in forcing the material into the cans cut off communication with hopper tubes, 10, and also enter slightly into the cans. During this operation the excess juices will be displaced by the entering plunger-ends and carried off through the overflow passages, 40, into the overflow shells, and out through openings, 42 and nozzles 43, into the two empty cans next to be filled. The table, 47, is then lowered, and as two new cans are forced onto the table, the filled cans will be pushed off onto a conveyor or support, 82, to receive them while the two cans which received the overflow from the filled cans last removed, will move to filling position.

It will thus be seen that two cans are filled at a time and are held in an inclined position during the filling operation so that the overflow may be readily carried back to the next two cans to be filled.

In the present instance the can feed devices comprise a vertical chute, 75, down through which the cans are fed while in a horizontal position and beneath which is located a curved table or support, 76, having inclined walls, 77. A rotary member, 78, is sustained so as to rotate in a horizontal plane over said table or support, and said member is provided with two arms, 79, and 80,—the latter of which is longer than the former. A curved channel or guideway, 81, extends laterally from the table or support and terminates beneath the horizontal can friction plate, 70, and, 71.

As the cans drop onto the table, 76, on their side, they are engaged by one or the other of the arms, 79, or, 80, and swept around the table. During this travel, the open end of the can rides up the inclined side of the table wall and gradually rights itself until it finally turns up on its end and is pushed laterally onto the guideway, 81. One can is pushed beneath the friction plate, 70, by the can next behind it and a third can is fed under the plate, 70, before the plunger heads, 67, move forward. In this way the cans are righted and fed in such time that two cans will be located in front of the plunger heads by the time the latter are moved forward. This feed device is fully explained in a companion application executed and filed simultaneously herewith and a detailed description is therefore believed to be unnecessary herein.

Having thus described my invention what I claim and desire to secure by Letters Patent is:—

1. In a can filling machine, the combination with a hopper having an outlet, of a plunger for said hopper outlet; an overflow shell at the hopper outlet said shell having an inclined position with two outlets therein one of which outlets is in a plane higher than the other; a swinging

70

125

130

support to sustain a can for each of said shell-outlets; means for moving the support to present the cans in an inclined position to said two outlets; means for operating the support and means for feeding cans onto the support.

2. In a can-filling machine, the combination with a hopper having an outlet, of a plunger for said hopper outlet; an overflow shell at the hopper outlet said shell having an inclined position with two outlets therein, one of which outlets is in a plane higher than the other; a stationary can-sustaining table; a swinging can-sustaining table; means for moving the cans from the stationary table onto the swinging table; means for moving the swinging table to present one can to the higher shell-outlet and another can to the lower shell-outlet.

3. In a can-filling machine, the combination with a hopper having an outlet, of a plunger for said hopper outlet; an inclined shell at the hopper outlet and said shell having two outlets one of which is in a plane higher than the other; a can sustaining table pivotally supported beneath the shell; means for intermittently feeding cans onto the table; means for swinging the table upwardly to present one can to the higher shell-outlet and to present another can to the lower shell-outlet and to hold the higher can in an inclined position and means for forcing material into the higher can.

4. In a can-filling machine, the combination with a hopper having a plurality of outlets, of a plunger for each hopper-outlet; an inclined overflow shell at each hopper outlet and each shell having two openings therein one of which openings is in a plane higher than the other; means for presenting cans to the higher outlet of each shell and simultaneously presenting other cans to the lower outlet of each shell and means for simultaneously actuating the plunger to each hopper-opening.

5. In a can-filling machine, the combina-

tion with a hopper having a plurality of outlets, of a plunger for each hopper-outlet; an inclined overflow shell at each hopper outlet and each shell having two openings therein one of which openings is in a plane higher than the other; a swinging table below all of the shells; means for feeding as many cans onto the table at a time as there are higher shell-openings, means for swinging the table upwardly to present a can to each higher shell-opening and another can to each lower shell-opening and means for actuating the plungers.

6. In a can-filling machine, the combination with a hopper having a plurality of outlets, of a plunger for each hopper-outlet; an inclined overflow shell at each hopper outlet and each shell having two openings therein one of which openings is in a plane higher than the other; a plunger for each hopper outlet; means for actuating all of the plungers simultaneously to project them through the higher outlets of the shells and means for presenting cans to the higher outlet of each shell and simultaneously presenting other cans to the lower outlet of each shell whereby the overflow from the cans at said higher outlets may flow through the shells and out through the lower outlets thereof.

7. In a can-filling machine, the combination with a hopper having a plurality of outlets, of a plunger for each outlet; an inclined overflow shell for each hopper-outlet; a swinging table below the overflow shells; means on the table for clamping a series of cans thereon and means for swinging the table and the clamped cans toward the shells to position some of them for filling and to hold others to receive the overflow.

In testimony whereof I affix my signature in presence of two witnesses.

CHARLES H. AYARS.
